Primary Examiner—Philip S. Hyder*Assistant Examiner*—R. L. [Ulm] Cody(74) *Attorney, Agent, or Firm*—Morrison & Foerster LLP(57) **CLAIM**

The ornamental design for a media cartridge protective case, as shown and described.

DESCRIPTION

FIG. 1 is a top perspective view of a media cartridge protective case showing our new design (with a closing tab in an open position);

FIG. 2 is a bottom perspective view thereof;

FIG. 3 is a front view thereof;

FIG. 4 is a back view thereof;

FIG. 5 is a left/right side view thereof;

FIG. 6 is a top view thereof;

FIG. 7 is a bottom view thereof; and,

FIG. 8 is a cross-sectional view thereof taken along line 8—8 of FIG. 6 and showing a shock absorbing member and media cartridge therein.

The broken lines shown in FIG. 8 are for illustrative purposes only and form no part of the claimed design.
